UNITED STATES PATENT OFFICE.

CHARLES S. SHAPIRO, OF NEW YORK, N. Y.

DESIGN FOR A PANEL-CURTAIN.

49,553.

Specification for Design. Patented Aug. 22, 1916.

Application filed May 31, 1916. Serial No. 100,970. Term of patent 3½ years.

To all whom it may concern:

Be it known that I, CHARLES S. SHAPIRO, a citizen of the United States, residing at New York, in the county of New York and State of New York, have invented a new, original, and ornamental Design for Panel-Curtains, of which the following is a specification, reference being had to the accompanying drawings, forming part thereof.

The figure is a front elevation of a panel curtain showing my new design.

I claim:—

The ornamental design for a panel curtain as shown.

CHAS. S. SHAPIRO.
